ARM HOLDING MEANS FOR EMBALMING BODIES PREPARATORY TO BURIAL

Don P. Marler, University City, Mo., assignor to Royal Bond, Inc., St. Louis, Mo., a corporation of Missouri

Application May 10, 1956, Serial No. 584,039

9 Claims. (Cl. 27—21)

This invention relates in general to certain new and useful improvements in arm holding means for embalming bodies preparatory to burial and, more particularly, to novel means and methods for restraining and positioning the arms of the corpse during various embalming operations.

In the embalming of bodies, the embalmer frequently encounters difficulty in restraining and positioning the arms of the corpse. For a period of several hours after death the muscles and tissues are soft and flexible and become progressively harder until rigor mortis finally occurs making it necessary for the embalmer to reposition the arms from time to time. Furthermore, after the body has been dressed by the embalmer and it is being placed in the coffin or casket, the arms are often displaced by the movement and make it very difficult to transfer the body from the embalming table.

It is, therefore, the primary object of this invention to provide arm holding means for restraining the arms of the corpse during the embalming and dressing procedures.

It is also an object of the present invention to provide means for positioning the arms of the corpse during embalming, which means is relatively inexpensive and simple to use, and which efficiently holds the arms in position while the body is being moved from place to place during dressing and placement in the coffin.

It is another object of the present invention to provide arm holding means of the type stated which can be readily cleaned and sterilized and will not become permanently soiled or fouled when used on bodies which have undergone post-mortem operations.

With the above and other objects in view, my invention resides in the novel features of form, construction, arrangement, and combination of parts presently described and pointed out in the claims.

In the accompanying drawing—

Fig. 1 is a perspective view of the arm holding means constructed in accordance with and embodying the present invention;

Fig. 2 is a fragmentary sectional view taken along line 2—2 of Fig. 1;

Figs. 3 and 4 are diagrammatic views of the arm holding means in two different operative positions;

Fig. 5 is a fragmentary perspective view of a modified form of the present invention; and

Fig. 6 is a diagrammatic view showing the modified form of the present invention in operative position.

Referring now in more detail and by reference characters to the drawing, which illustrates a practical embodiment of the present invention, A designates an arm holding device comprising two arm grapples 1 and 2 respectively provided with straps 3 and 4 which are adjustably connected by means of a buckle 5 or any other suitable fastening device. The arm grapple 1 is preferably formed of aluminum bar-stock and integrally includes two hook members 6 and 7 connected by an arcuate bight 8 having a skewed curvilinear, somewhat V-shaped, contour. The

arm grapple 2 is also formed of aluminum bar-stock, in shape is a mirror image or asymmetric duplicate of the arm grapple 1 and integrally include two hook members 9 and 10 connected by an arcuate bight 11. Thus when the arm grapple 1 is operatively engaged with one arm of the corpse, the other arm grapple 2 will similarly engage the other arm of the corpse. As will be seen by reference to Fig. 1, the straps 3, 4, are respectively turned back at ends around the bights 8, 11, and riveted or otherwise similarly secured in the formation of loops 12, 13, respectively. It should be noted that the arm grapples 1, 2, are each of non-symmetrical shape so that they may be shifted within the loops 12, 13, to various desired relative positions, thereby making it possible to dispose the arms of the corpse in many different positions of repose.

In use the arm grapples 1, 2, are hooked beneath the arms of the corpse and shifted with respect to the loops 12, 13, to hold the arms in some suitable or artistic posture. At the same time the distance between the arm grapples 1, 2, may be suitably adjusted by buckling the straps 3, 4, together in the desired position. With the arms thusly held, the corpse may be embalmed and dressed in preparation for burial. Thereafter, when it becomes necessary to transfer the corpse to a coffin, the arms will remain in position. It is to be noted that a great variety of different arm positions can be obtained by various adjustments of the straps 3, 4, and the relative positions of the arm grapples 1, 2, two of such positions being shown in Figs. 3 and 4.

It is also possible to provide a modified form of the present arm holding device A' as shown in Figs. 5 and 6. The arm holding device A' comprises arm grapples 1', 2', substantially similar in structure and shape to the previously described arm grapples 1, 2. The arm grapples 1', 2', are respectively provided with cavity-hooks 14, 15, having terminal loops 16, 17, for encircling engagement with the arm grapples 1', 2', respectively. The cavity hooks 14, 15, are designed to engage with the edges of the visceral incision in post-mortem corpses as best seen in Fig. 6.

It should be understood that changes and modifications in the form, construction, arrangement, and combination of the several parts of the methods and means for embalming bodies preparatory to burial may be made and substituted for those herein shown and described without departing from the nature and principle of my invention.

Having thus described my invention, what I claim and desire to secure by Letters Patent is:

1. For use in embalming corpses, an arm holding device comprising an arcuate somewhat V-shaped member curved up at its outer extremities in the formation of hook-like elements adapted to extend under and engage the arm of a corpse on opposite sides of the elbow, and means for securing said member at the side of the abdominal portion of said body in the region of the elbow.
2. For use in embalming corpses, an arm holding device comprising an arcuate somewhat V-shaped member curved up at its outer extremities in the formation of hook-like elements adapted to extend under and engage the arm of a corpse on opposite sides of the elbow, and means for adjustably securing said member at the side of the abdominal portion of said body in the region of the elbow.
3. For use in embalming corpses, an arm holding device comprising an arcuate somewhat V-shaped member curved up at its outer extremities in the formation of hook-like elements adapted to extend under and engage the arm of a corpse on opposite sides of the elbow, and strap means for securing said member at the side of the abdominal portion of said body in the region of the elbow.
4. For use in embalming corpses, an arm holding device

comprising an arcuate somewhat V-shaped member curved up at its outer extremities in the formation of hook-like elements adapted to extend under and engage the arm of a corpse on opposite sides of the elbow, and hook-means for securing said member at the side of the abdominal portion of said body in the region of the elbow. 5

5. For use in embalming corpses, an arm holding device comprising a pair of arm grapples adapted to extend along the sides of the chest of the corpse and engage the arms thereof, said arm grapples being of skewed curvilinear somewhat V-shaped contour and being mirror-images with respect to each other, and means for holding said arm grapples upon the corpse. 10

6. For use in embalming corpses, an arm holding device comprising an arcuate somewhat V-shaped member curved up at its outer extremities in the formation of hook-like elements adapted to extend under and engage the arm of a corpse on opposite sides of the elbow, and means for securing said member at the side of the abdominal portion of said body in the region of the elbow, said means engaging the V-shaped member loosely so that the V-shaped member can be shifted endwise in said means for varying the arm holding position thereof. 15

7. For use in embalming corpses, an arm holding device comprising an arcuate somewhat V-shaped member curved up at its outer extremities in the formation of hook-like elements adapted to extend under and engage the arm of a corpse on opposite sides of the elbow, and strap means for securing said member at the side of the abdominal portion of said body in the region of the elbow, said strap means engaging the V-shaped member loosely so that the V-shaped member can be shifted endwise in said strap means for varying the arm holding position thereof. 20

8. For use in embalming corpses, an arm holding device comprising an arcuate somewhat V-shaped member curved up at its outer extremities in the formation of hook-like elements adapted to extend under and engage the arm of a corpse on opposite sides of the elbow, and strap means for securing said member at the side of the abdominal portion of said body in the region of the elbow, said strap means being provided at its ends with a closed loop which encircles the V-shaped member intermediate the curved extremities thereof so as to permit the V-shaped member to be shifted endwise with respect to the strap for adjusting the arm holding position thereof.

9. For use in embalming corpses, an arm holding device comprising an arcuate somewhat V-shaped member curved up at its outer extremities in the formation of hook-like elements adapted to extend under and engage the arm of a corpse on opposite sides of the elbow, and hook-means for securing said member at the side of the abdominal portion of said body in the region of the elbow, said hook means engaging the V-shaped member loosely so that the V-shaped member can be shifted endwise in said hook means for varying the arm holding position thereof.
